UNITED STATES PATENT OFFICE.

FRANK W. MIX, OF NEW BRITAIN, CONNECTICUT.

TRUNK-LID LIFTER AND CUP OR HASP PLATE FOR TRUNK-LOCKS.

SPECIFICATION forming part of Letters Patent No. 365,533, dated June 28, 1887.

Application filed November 8, 1886. Serial No. 218,297. (No model.)

To all whom it may concern:

Be it known that I, FRANK W. MIX, of New Britain, in the county of Hartford and State of Connecticut, have invented certain new and 5 useful Improvements in Trunk-Lid Lifters and Cup or Hasp Plates for Trunk-Locks; and I do hereby declare the following to be a full, clear, and exact description of the invention, such as will enable others skilled in the art to which it 10 appertains to make and use the same.

My invention relates to a trunk-lid lifter and cup or hasp plate for trunk-locks.

In a form of trunk-locks that have their locking mechanism inserted in a recess formed in 15 a hinged hasp-plate that has its lower hinged portion made to be rigidly attached to the front of a trunk, a suitable cup-plate is required to receive the body of the upwardly swinging hasp-lock and afford a retaining-catch 20 for the lock, this cup-plate being attached to the front board or vertical side of the trunk-lid.

The object of my present invention is to construct a cup-plate for a lock of the description named with a lifting-catch for the accommodation 25 of the fingers of a person opening the trunk, making this lid-lifter either an integral portion of the recessed cup-plate or forming it in a separate piece to be afterward rigidly secured to the front surface of the cup-plate.

With this end in view my invention consists 30 in certain features of construction and combination of parts that will be hereinafter described, and pointed out in the claim.

In the drawings making a part of this specification, Figure 1 is a front elevation of the combined lifter-ledge and cup-plate stamped 35 entire from one piece of sheet-plate. Fig. 2 is a cross-section of the device with the lifter made integral with the cup-plate. Fig. 3 is a face view of the attached lifter and cup-plate. Fig. 4 is a cross-section of the attached lifter 40 and cup-plate. Fig. 5 is a view of the lid-lifter and the cup-plate of a lock with the lock-body and its depending hasp-plate locked in 45 secure position on the plate.

A represents the cup-plate, made of sheet metal cut into form and raised by cutting and forming dies, or this plate A may be cast of any suitable metal, as may be preferred. The 50 design or shape of this plate A may be modified to suit the taste of the manufacturer. A

preferred form is shown in the drawings in Figs. 1 and 3. The plate is perforated near its edge with a proper number of holes for screws or clinch-nails by which to firmly secure it in 55 position on the front board of the lid of a trunk or box. The cup or recess B is made a suitable depth and of such form in its side wall as will fit properly the lock-body it is to receive, and the back wall thereof is provided centrally with an opening, D, adapted to register with the turn-buckle of the lock that enters this opening, and is made to catch upon the rear face of the cup-plate A by a partial revolution of the key, causing the turn-buckle 60 to overlap upon the edges of the cup-plate. (See Fig. 5.)

Near the upper edge of the plate A a hand-pull or lifter, C, for lifting the lid of the trunk or box, is located. This hand-pull is preferably given the form shown in Figs. 1, 2, 3, and 4. It consists of a piece of sheet metal of proper shape struck up with dies, or it may be cast into form, as may be preferred. The hand-pull or lifter may be made integral of a piece 70 of sheet-plate that is also a cup-plate, and is shaped by cutting and forming dies on a proper press. The preferred form for this piece, as shown in the figures, is a concavo-convex lip or flange, C, of such length and projection from 75 its supporting-plate A that the fingers of the user may be readily inserted beneath the curved flange C, and the lid raised by the purchase afforded on this appendage to the cup-plate A. The hand-pull or lifter and cup-plate may also 80 be cast integral; but in some cases it is preferred to cast both the cup-plate and the lifter or hand-pull separate, in order to facilitate the finishing operations of their manufacture. The cup-plate and hand-pull when so made are 85 rigidly secured in contact after finishing up to this point by rivets or any other suitable manner to properly attach them together.

I do not desire to restrict myself to any special design in the formation of either the hand-pull for lifting the lid or the style or shape of the cup or hasp plate of a lock. 90

I am aware that it is old to provide a hasp with guiding and locking lugs and with a handle for lifting the lid, the lugs adapted to enter 100 sockets in the lock-casing; also, that it is old to provide a sectional rim adapted to be se-

cured to the trunk body and lid around the lock with a handle, and also that it is old to provide the cup-plate of a hasp-lock with a ring, the latter being pivoted to the cup-plate 5 and adapted to be turned upwardly for lifting the lid after the lock-case has been withdrawn from the cup-plate, and hence I make no claim to such construction.

Having fully described my invention, what I claim as new, and desire to secure by Letters Patent, is—

As a new article of manufacture, a plate provided on its front face with a cup-shaped recess conforming in shape to and adapted to receive the body of a swinging lock, the back wall of said recess having an opening adapted

to register with the turn-buckle of the lock, the said plate being also provided at a point above said recess with an outwardly-projecting rigid flange forming a handle or finger-hold 20 for lifting the lid, and provided on its rear face with a projection conforming in shape to the recess in the front face of the plate, substantially as set forth.

In testimony whereof I have signed this 25 specification in the presence of two subscribing witnesses.

FRANK W. MIX.
